MOBILE WHEEL ALIGNMENT UNIT

Oklahoma Moore, Pasadena, Tex., assignor to
Don Seitz, Pasadena, Tex.

Filed Nov. 7, 1967, Ser. No. 9,313

Term of patent 14 years

(Cl. D14—3)

FIG. 1 is an isometric view of the front, top and one side of a mobile wheel alignment unit, showing my new design in operative position for servicing;

FIG. 2 is an isometric view of the rear, bottom, and the same side thereof, with the gauge panel shown in FIG. 1 being omitted for purposes of clarity; the other side appearing in correspondence with the side shown with the gauge panel omitted; and

FIG. 3 is a fragmentary isometric view of the front portion of the ramp, correspondingly as shown in FIG. 1, as arranged for a vehicle to drive off forwardly after service.

I claim:

The ornamental design for a mobile wheel alignment unit, as shown and described.
